UNITED STATES PATENT OFFICE.

JOSEPH SZAKÁCS, OF WOOD, PENNSYLVANIA, ASSIGNOR OF ONE-THIRD TO NICHOLAS GENSIOR, OF WOOD, PENNSYLVANIA, AND ONE-THIRD TO W. IRA EVANS, OF BROAD TOP, PENNSYLVANIA.

PADLOCK.

Application filed October 15, 1925. Serial No. 62,607.

This invention relates to new and useful improvements in padlocks.

The primary object of the invention is to provide improved forms of padlocks of the sliding shackle type having novel means for holding the shackle in its closed or locked position.

A further object of the invention is the provision of novel means for releasing the shackle from its holding means.

Other objects and advantages of the invention will be apparent during the course of the following description.

In the accompanying drawings forming a part of this specification and in which like numerals are employed to designate like parts throughout the same,

Figure 1 is a side elevational view of a padlock embodying this invention,

Figure 2 is a top plan view of the lock shown in Fig. 1,

Figure 3 is a longitudinal sectional view, partly in elevation, of the structure shown in Figs. 1 and 2,

Figure 4 is a transverse sectional view of the above referred to type of padlock and illustrates the manner in which the key engages and operates the shackle holding means,

Figure 5 is a similar view to Fig. 2 but shows the padlock with the key removed and a key hole guard or cover shifted to prevent the insertion of the key,

Figure 6 is a side elevational view of a modified form of padlock,

Figure 7 is a side elevational view of the padlock shown in Fig. 6, but taken at right angles thereto,

Figure 8 is a longitudinal sectional view of the type of padlock shown in Figs. 6 and 7,

Figure 9 is a transverse sectional view of this type of padlock.

Figure 10 is an elevational view of the type of key employed for unlocking the padlock shown in Figs. 6 to 9 inclusive,

Figure 11 is a further modified form of padlock, shown in side elevation,

Figure 12 is a side elevational view of the padlock shown in Fig. 11, but taken at right angles thereto,

Figure 13 is a top plan view of the padlock shown in Figs. 11 and 12,

Figure 14 is a bottom plan view of this padlock,

Figure 15 is a vertical sectional view taken upon line XV—XV of Fig. 13,

Figure 16 is a vertical sectional view taken upon line XVI—XVI of Fig. 11,

Figure 17 is a transverse sectional view taken upon line XVII—XVII of Figure 16, and

Figure 18 is a transverse sectional view taken upon line XVIII—XVIII of Figure 16.

In the drawings, wherein for the purpose of illustration is shown a preferred embodiment of this invention, the numeral 5, in Figs. 1 to 5 inclusive, designates a padlock casing which is closed at its inner end 6 and is formed with the shackle side receiving openings 7 at its remaining end. Pivottally mounted within the casing 5, upon the pin 8, is a V-shaped leaf spring 9 which is formed at its ends into triangularly-shaped enlargements 10 having laterally inwardly projecting ears 11, as illustrated. Figure 4 shows the casing 5 as having formed there-in the elongated, transversely extending key hole 12 which registers with the eyes 11 of the spring 9.

A shackle 13 is associated with this padlock and has its opposite legs 13^a formed with transversely alined notches 14 into which the spring enlargements 10 are intended to project, when the shackle is inserted into the casing 5 through the openings 7, for preventing the withdrawal of the shackle.

The type of key employed for releasing the shackle 13 includes a body portion 15 which is formed with the tubular section 16 and the U-shaped end portion 17, the sides of this U-shaped end portion being provided with alined apertures 18 which are also axially alined with the tubular portion 17.

A sliding rod 19 is inserted through the tubular portion 16 and has its end portion 20 screw-threaded and located within the alined apertures 18. The extremity of this threaded portion 20 is formed with an eye 21 by means of which the key may be fastened to a key ring, or the like. The extreme end of the tubular portion 16 of the body 15 is formed with a laterally projecting finger 22 while the extreme end of the

rod 19, designated by the numeral 23, is formed with a laterally projecting finger 24 extending in parallelism with the finger 22. Positioned upon the threaded portion 20 of the slideable rod 19, and located between the sides of the U-shaped end portion 17, is a wheel 25 which is threaded connected to the threaded portion 20. It will now be seen that by inserting the fingers 22 and 24 of the relatively movable portions of the lock within the eyes 11 of the spring end enlargements 10 and by rotating the wheel 25 to cause longitudinal movement of the rod 19 which will move the fingers 22 and 24 toward each other, the enlargements 10 of the leaf spring 9 may be forced toward each other to extract the said enlargements from the shackle notches 14. After these enlargements 10 have been removed from the notches 14, the shackle may be withdrawn from the casing 5. After the shackle has been withdrawn, the key may be moved to extract its fingers 22 and 24 from the eyes 11. The shackle may then be inserted into the lock and the extremities of its leg portions will force the enlargements 10 toward each other until the notches 14 are placed in alignment with the same, whereupon the enlargements will then enter the notches.

Rotatably connected to the casing 5, by the pin 26, is a drum-shaped key hole cover or guard 27 which is provided with an opening 28 in its side wall. This key hole cover or guard 27 is intended to be located with the notch in transverse alignment with the key hole 12 for permitting the key to be inserted into the guard and arranged with its fingers 22 and 24 received within the eyes 11. When the key is not inserted into the guard and casing and the shackle is locked to the casing, the key hole guard or cover 27 may be rotated upon the pin 26 for moving its opening 28 out of transverse alignment with the elongated slot or key hole opening 12. The key then cannot be inserted into the lock.

In Figures 6 to 10 inclusive the reference character 29 designates a casing which is closed at its inner end 30 and is open at its outer end 31. The diametrically opposed edges of the open end 31 are provided with cutout portions 32, the function of which will be disclosed at a later point. A strap of substantially inverted U-shape, 33 is suitably connected to the casing 29 to extend longitudinally thereof with its base or closed end 34 straddling the open end 31 of the casing to close the same with the exception of suitable openings left for the insertion of the sides 35 of the substantially U-shaped shackle 36. The opposite sides of this shackle 36 are formed with transversely aligned notches 37.

Pivots mounted within the casing 5,

upon the pin 38, is a substantially V-shaped leaf spring 39 which has one of its ends formed with an enlargement 40 that is provided with the laterally, oppositely extending lugs 41. The remaining end of this leaf spring 39 is of arcuate formation, as at 42. It will be seen, by inspecting Figs. 6, 8 and 9, that the lugs 41 carried by the enlargement 40 project outwardly of the casing through the cutaway portions 32. The strap 33 is bent outwardly at 33^a to form covers or guards for the cutaway portions 32 and to further clear or cover up and conceal the lugs 41. It will now be seen that the shackle 36 may be inserted into the casing 29 and the enlargement 40 carried by the leaf spring 39 will enter the particular notch 37 placed in register with the same. Both legs 35 of the shackle 36 are provided with notches 37 so that the legs 35 may be inserted into the casing 29 with either side adjacent the spring enlargement 40.

Figure 10 clearly shows the type of key employed for releasing or unlocking the shackle 36. This key includes a ring portion 42 which has projecting therefrom the parallel fingers 43 having notches 44 cut in their end edges. By inserting the fingers 43 into the spaces provided by the laterally bent portions 33^a of the strap 33 and locating the lugs 41 in the notches 44 of the key fingers 43, the fingers may be moved longitudinally for forcing the enlargement 40 toward the arcuate end 42 of the leaf spring. This movement of the enlargement 40 will extract the same from the notch 37 and the shackle 36 will be released.

In Figs. 11 to 18 inclusive, the numeral 45 designates a lock casing which is closed at its inner end 46 with the exception of the aperture 47 and is closed at its outer end 48 by the disk 49. This disk 49 is held in place by a post 50 which is journaled in the disk and in the aperture 47, formed in the closed end 46 of the casing. The disk 49 is further provided with openings 51 which receive the sides 52 and 53 of the shackle 54. A further opening 55 is formed in the disk 49 and its function will be described at a later point. The leg 53 of the shackle 54 is cutaway at 56, at its extremity, to form with the lug 57 a notch. It will be seen by inspecting Figures 15 and 17 that this lug 57 is of less width than the shackle leg 53 and is carried by an enlargement 58 suitably secured or formed integrally with the end of the shackle leg 53.

Mounted upon the post 50 and secured thereto by the pin 59 is a disk 60 which is formed with the peripheral notch 61. A sleeve 62 is also mounted upon the post 50 and is interposed between the upper face of the disk 60 and the inner face of the disk 49. Slidably positioned within the opening 55, formed in the disk 49, is a pin 63 hav-

ing the ring like abutment 64 spaced inwardly from its inner end. The spring 65 encircles the pin 63 and bears at one end against the abutment 64 and at its other end against the inner face of the disk 49. It will be seen that this spring functions to force the inner extremity of the pin toward the disk 60. The post 50 has an operating head 66 formed on its outer end while one face thereof is provided with the indenture 67. This indenture registers or is in alinement with the notch 61 and is intended to indicate the location of the latter. Figure 12 shows the side 53 of the shackle 54 as having a cross 67 formed therein. This cross 67 is merely intended to distinguish the side 53 from the side 52.

To lock the shackle 54 to the casing 45, the disk 60 must first be operated by the head 66 of the post 50 for locating the disk notch 61 in alinement with the lug 57 of the shackle leg 53. This lug may then be passed through the notch 61 for locating the lug inwardly of the disk. The disk may then be rotated for disalining the lug 57 and notch 61 and the disk should be moved until the notch 61 registers with the inner extremity of the pin 63. The spring 65 will then force this extremity into the notch 61 and the disk 60 will be prevented from rotating until the pin extremity is extracted from the notch. To unlock the shackle 54, the above operation is merely reversed.

It is to be understood that the forms of

this invention herewith shown and described are to be taken as preferred examples of the same, and that various changes in the shape, size, and arrangement of parts may be resorted to without departing from the spirit of the invention or the scope of the subjoined claims.

Having thus described the invention, I claim:—

1. In a padlock of the type described, a casing having a pair of shackle leg receiving openings, a U-shaped shackle having a notch formed in each leg thereof, a V-shaped leaf spring connected at its base to the casing, an enlargement carried by each end of the spring and adapted to enter the notches in the shackle legs, and a key insertable into the casing for connection with the enlargements to force the latter toward each other and out of the notches.

2. In a padlock of the type described, a casing having a pair of shackle leg receiving openings, a U-shaped shackle having a notch formed in each leg thereof, a V-shaped leaf spring connected at its base to the casing, an enlargement carried by each end of the spring and adapted to enter the notches in the shackle legs, an eye carried by each enlargement, and a key having relatively movable fingers adapted to enter said eyes for forcing the enlargements toward each other and out of the notches.

In testimony whereof I affix my signature.

JOSEPH SZAKÁCS.
